UNITED STATES PATENT OFFICE.

WILLIAM F. KIESEL, JR., OF ALTOONA, PENNSYLVANIA.

STEAM-ENGINE.

1,307,821.

Specification of Letters Patent. Patented June 24, 1919.

Application filed April 4, 1916. Serial No. 88,869.

To all whom it may concern:

Be it known that I, WILLIAM F. KIESEL, Jr., a citizen of the United States, and resident of Altoona, Blair county, State of Pennsylvania, have invented certain new and useful Improvements in Steam-Engines, of which the following is a specification.

This invention relates to improvements in valve construction for steam engines, especially locomotives. The object is similar to that accomplished by the structure described in the patent to Haughton No. 536,622 granted April 2, 1895, but a different and much simpler means is used. The invention is illustrated in connection with a piston valve construction although it is obvious that it can be used in other forms of valves.

In the common type of valve actuated through some form of reversing gear, if the valve is designed to give a cut-off at half stroke or less at full gear, there are positions at which the engine may stop, and steam will not be admitted to the cylinders. Even in engines having three cylinders, there are positions in which the engine may stop, such that the starting effort will be less than that desired. Hence in engines having cut-offs at half stroke or less when in full gear, in order to have the proper starting power, it is necessary to provide an auxiliary valve, or some other means, to admit steam into the cylinders at starting. This admission should occur after the main valve has closed the valve port at half stroke, up to at least three-quarters stroke.

To avoid the necessity of an auxiliary valve, and the additional complication of a separate mechanism for actuating the same, this invention has been made.

It consists of the provision of an auxiliary port, opening into the valve steam space and arranged to be closed after the main port, so that steam may flow through the same and into the engine cylinder after cut off at the main port and until the piston has traveled any desired part of its stroke, for example 80%.

Another feature of the invention resides in the size of the auxiliary port. It may be made so that the cross-sectional area is small relative to that of the main port.

In the drawings, in which like reference characters indicate like parts in the different views,

Figure 1 is a longitudinal sectional view through the valve and showing the top portion of the engine cylinder;

Fig. 2 is a horizontal sectional view through a portion of the valve cylinder and showing the arrangement of the auxiliary port.

The drawings illustrate the invention as applied to a common construction of piston valve. The valve cylinder 10 is provided with the usual steam and exhaust connections (not shown). In the form shown the steam space 11 is centrally arranged. Hence the valve takes steam on the inside. The exhaust spaces 12, 13, are located at the ends of the valve cylinder.

At each end the cylinder is provided with liners or bushings 14, 15, which are formed with the usual port openings 16 leading to the main ports 17. These main ports lead to the ends of the engine cylinder 18. A piston 19 of the usual form in valve construction slides in the bushings 14, 15, being operated by the valve rod 20. This valve rod may be actuated by any of the valve gears commonly used in engine construction.

The invention as applied to a valve construction as described above consists in the provision of an auxiliary port 21 having the port opening 22 through the valve liner. As shown this auxiliary port is located between the edge of the main port and the admission edge of the valve when the valve is in mid position. Furthermore, as clearly illustrated in Fig. 2, the port opening 22 is of small cross-sectional area as compared to the main port openings 16. This auxiliary port leads from the valve cylinder to the main port, thereby providing a connection between the valve and engine cylinders, in addition to that provided by the main port alone.

This invention has particular utility in engines which are designed with a maximum cut-off which is rather early, for instance half stroke. The valve 19 is illustrated with a large steam lap, which will give an early cut-off, at the main port. However, after cut-off has occurred at the main port, steam will continue to be supplied to the engine cylinder, through the auxiliary port opening 22. The location of the latter port will determine when cut-off will occur at this auxiliary port. It is obvious that it may be located so that steam will be supplied to the engine cylinder for almost the entire stroke, and even

though cut-off at the main port occurred at half stroke. In a locomotive which is designed to give cut-off say at half stroke or less in full gear, steam may therefore be supplied for the greater part of the stroke, thereby giving a more uniform torque at starting and avoiding any dead points.

As previously stated, the cross-sectional area of the auxiliary port 22 is small as compared to the cross-sectional area of the main port. This is an important feature of the invention. If the engine or locomotive should stop in such a position that the valves in all cylinders cover the main ports, and no steam can enter the engine cylinder through the main port openings 16, steam can flow through the auxiliary port 21 and act on the engine piston, thereby starting the engine. As the speed of the engine increases, less and less steam will flow through the auxiliary port. Above some speed, depending on the relative areas of the ports, the steam passing through the auxiliary port will be a negligible quantity. The action of the engine or locomotive at this higher speed will be governed entirely by the cut-off at the edge of the main port openings 16. It will be observed that the port 22 is not only in advance of the admission edges of the main port-openings but is also separated therefrom. Furthermore, the dimension of the opening in the direction of the valve travel is small compared with the dimension in the direction transverse of the valve travel. Because of this location and shape of the auxiliary port its area may be a minimum to accomplish the desired result of having the engine make its first revolution from rest. Further, because of the small area, the effect of the auxiliary port after

the first revolution and as the engine gathers speed is practically *nil*.

In view of the foregoing description, the operation of the device should be quite apparent. The result of the use of the auxiliary port is that at starting or at very slow speeds, say less than a mile per hour, the effect of the combination of the main port and the auxiliary port is to give a long cut-off. At higher speeds, however, say five or more miles per hour, on account of the wire drawing effect of steam through the small auxiliary port, practically no steam flows through this port, and the valve operates as though there is a main port only, giving an early cut-off.

Having thus described the invention what is claimed and desired to be secured by Letters-Patent is:—

In a valve construction for steam engines having a valve chamber, a main port connecting the said chamber and the cylinder, and a slideable valve controlling said port; improved means for supplying steam to the engine cylinder after cut-off at the main port and for automatically decreasing the said supply of steam as the engine speed increases, consisting of an auxiliary port-opening in advance of the admission edges of the main port-opening and separate therefrom, said auxiliary port-opening being small relative to the main port-opening, its dimension in the direction of valve travel being short relative to the dimension in the direction transverse to the valve travel and the main port being formed with a recess adapted to afford a connection between the auxiliary port-opening and the main port.

In testimony whereof I affix my signature.
WILLIAM F. KIESEL, JR.
